SPEAR

Filed July 13, 1928

UNITED STATES PATENT OFFICE.

ERCOLE VENTRESCA, OF HOUSTON, TEXAS.

SPEAR.

Application filed July 13, 1928. Serial No. 292,422.

My invention relates to improvements in spears to be employed in deep well operations.

It is an object of my invention to provide 5 a spear to be employed in removing pipe, such as drill stem or casing, from the well. It may be employed as a fishing tool to engage pipe broken off in the well, or may be employed in pulling casing when a well is 10 abandoned. It is adapted for insertion downwardly within the pipe and to be then expanded to engage the pipe so as to allow the pipe to be pulled from the well.

It is an object of the invention to provide 15 a spear which may be readily expanded to engage the pipe and which may be also readily released to be disengaged from the pipe if the pipe is lodged in the well so that it may not be removed.

20 The invention resides particularly in the simple construction of the device and the positive manner in which it may be operated without failure in use.

Referring to the drawing herewith where- 25 in a preferred form of my device is disclosed, Fig. 1 is a central longitudinal section through a spear, embodying my invention. Fig. 2 is a transverse section on the plane 2—2 of Fig. 1. Fig. 3 is a transverse 30 section on the plane 3—3 of Fig. 1.

In the construction of my device I employ a central tubular mandrel 5 which may be made of heavy pipe, the upper end being threaded at 6 for engagement with a releasing sleeve 7. The lower end is also threaded on its outer surface at 8 to engage with a nut or collar 9. At a point intermediate the ends of the mandrel I form a radially extending flange 10, having thereon an upper 35 shoulder 11, the purpose of which will be later explained.

Above the nut or collar 9 at the lower side is an upwardly tapered expanding sleeve 12. This sleeve is slidable upon the mandrel be- 45 tween the flange 10 and the nut 9 and its outer surface is tapered at 13 to receive the jaws 14 which are adapted to cooperate therewith.

The jaws 14 are arcuate in shape and, as 50 will be seen from Fig. 3, I have employed three such jaws. The inner surface of said jaws is tapered at the proper angle to fit upon the outer surface of the collar 12. Each jaw has an upwardly extending arm 55 15 connected with a ring 16 at the upper end,

said ring having an inwardly directed flange 17 to fit within a groove in the lower end of a sleeve 18. The jaws are thus loosely suspended and bear by gravity against the outer surface of the expanding sleeve 12.

The sleeve 18 upon which the jaws or slips 14 are supported is shaped to fit loosely over the mandrel 5 and to be slidable thereon. Said sleeve 18, as will be seen from Fig. 2 has along its outer surface a plurality of 65 vertical grooves or key-ways 19. Said key-ways extend from the upper end of the sleeve downwardly to a point indicated at 20 adjacent the lower end thereof and in these key-ways the flanges 16 upon the jaws or slips 70 14 may slide. At the lower end of the key-way the jaws will be supported upon the shoulders 20, as will be seen from Fig. 1. The upper end of the sleeve 18 is threaded with a coarse thread 21 which extends from 75 the upper end to a point about midway of the sleeve.

The releasing collar 7 which receives the upper end of the mandrel 5 is formed with an upper threaded shank 22 which is adapt- 80 ed to be engaged by a drill collar or other similar coupling. It is of materially larger diameter than the sleeve 21 and is formed with an inner thread 23 to engage with the thread 21 on said sleeve 18. The thread 23 85 is a short thread and I have shown but two turns of this thread on the releasing collar. Below the threads the portion 24 is a smooth surface adapted to slide over the sleeve 18.

In operating my device the sleeve 18 is 90 screwed downwardly in the releasing sleeve 7 so that the jaws 14 are free to slide upwardly along the key-ways therein. When the proper position in the well has been reached where the pipe is to be gripped the 95 device will be drawn upwardly and the engagement of the jaws 14 with the pipe will tend to pull them downwardly on the tapered surface 13 of the sleeve 12. This will tend to force the jaws into clamping engagement with the pipe so as to firmly grip the same. A further upward pull upon the spear will tend to pull the pipe thus engaged by the jaws in an upward direction and in this manner the pipe may be withdrawn from the well.

If, however, it is found that the pipe thus gripped cannot be removed and cannot be washed loose from the well through fluid pumped downwardly through the 100

central passage 25 the jaws will have to be released from their hold upon the pipe. This may be done by driving the collar 12 from beneath the jaws 14, allowing 5 the jaws to collapse. The collar may thus be driven from beneath the pipe gripping jaws by a downward thrust upon the mandrel 5. When the mandrel is thus forced downwardly it will carry with it the sleeve 10 18 which will move relative to the upper ring 16 of the jaws and the flange 10 on the mandrel will be brought against the upper end of the collar 12, tending to force it downwardly from between the jaws 14. A few 15 strokes of the mandrel in this manner will release the jaws. After this has been done the mandrel and releasing sleeve 7 will be rotated downwardly over the sleeve 18 to, in effect, draw said sleeve 18 together with 20 the jaws 14, upwardly away from the sleeve 12. When thus suspended above the expanding sleeve the jaws will fall inwardly away from the casing or pipe and the device may be easily withdrawn.

25 It will be noted that my device is certain and effective in its operation and will tend to function positively at all times. A feature of particular value connected therewith is the manner in which the jaws may 30 be released from the pipe when a release is desired. The provision for striking a blow upon the expanding sleeve 12 to allow the collapsing of the jaws 14 away from the pipe is particularly effective and will not fail in use.

35 Having thus described my invention, what I claim as new is:

1. A spear comprising a mandrel, an upwardly tapered expander sleeve slidable on the lower end thereof, a radial flange on said mandrel above said sleeve, a guide sleeve on said mandrel above said flange, a ring 40 slidable on said guide sleeve, slip jaws depending from said ring and shaped to fit upon said expander sleeve and to be forced outwardly to grip a pipe, said flange being adapted to be forced against said expander sleeve to jar it from beneath said jaws.
2. A spear comprising a mandrel, an upwardly tapered expander sleeve slidable on the lower end thereof, a radial flange on said mandrel above said sleeve, a guide sleeve on said mandrel above said flange, a ring 45 slidable on said guide sleeve, slip jaws depending from said ring and shaped to fit upon said expander sleeve and to be forced outwardly to grip a pipe, said flange being adapted to be forced against said expander sleeve to jar it from beneath said jaws,
3. A spear comprising a mandrel, an upwardly tapered expander sleeve slidable on the lower end thereof, a radial flange on said mandrel above said sleeve, a guide sleeve on said mandrel above said flange, a ring 50 slidable on said guide sleeve, slip jaws depending from said ring and shaped to fit upon said expander sleeve and to be forced outwardly to grip a pipe, said flange being adapted to be forced against said expander sleeve to jar it from beneath said jaws,
4. A spear comprising a mandrel, an upwardly tapered expander sleeve slidable on the lower end thereof, a radial flange on said mandrel above said sleeve, a guide sleeve on said mandrel above said flange, a ring 55 slidable on said guide sleeve, slip jaws depending from said ring and shaped to fit upon said expander sleeve and to be forced outwardly to grip a pipe, said flange being adapted to be forced against said expander sleeve to jar it from beneath said jaws,
5. A spear comprising a mandrel, an upwardly tapered expander sleeve slidable on the lower end thereof, a radial flange on said mandrel above said sleeve, a guide sleeve on said mandrel above said flange, a ring 60 slidable on said guide sleeve, slip jaws depending from said ring and shaped to fit upon said expander sleeve and to be forced outwardly to grip a pipe, said flange being adapted to be forced against said expander sleeve to jar it from beneath said jaws,

drel to retain said jaws away from said expander.

3. A spear including a mandrel, an upwardly tapered expander sleeve slidable 65 thereon, a plurality of slip jaws shaped to fit slidably upon said expander sleeve, means to support said jaws, and means on said mandrel to strike a blow upon said expander sleeve for the purpose described.

4. A mandrel, a guide sleeve thereon, an upwardly tapered expander sleeve on said mandrel below said guide sleeve, a ring 75 slidable on said guide sleeve, a plurality of jaws on said ring tapered on their inner faces to fit said expander sleeve and be expanded outwardly to grip a pipe, and means to drive said expander sleeve from beneath said jaws.

5. A mandrel, a guide sleeve thereon, an upwardly tapered expander sleeve on said 80 mandrel below said guide sleeve, a ring slid- able on said guide sleeve, a plurality of jaws on said ring tapered on their inner faces to fit said expander sleeve and be expanded outwardly to grip a pipe, and means to drive 85 said expander sleeve from beneath said jaws, said driving means including means on said mandrel operating on a downward movement thereof.

6. A mandrel, a guide sleeve thereon, an 90 upwardly tapered expander sleeve on said mandrel below said guide sleeve, a ring slid- able on said guide sleeve, a plurality of jaws on said ring tapered on their inner faces to fit 95 said expander sleeve and be expanded outwardly to grip a pipe, and means to drive said expander sleeve from beneath said jaws and means on said mandrel engaging said guide sleeve to move said sleeve and jaws upwardly, responsive to the rotation of said mandrel.

7. A spear including a mandrel, an ex- 100 pander sleeve thereon, means to support said sleeve, a guide sleeve on said mandrel, a plurality of jaws supported slidably but non-rotatably upon said guide sleeve, said jaws being adapted to fit upon said expander 105 sleeve and means on said mandrel engaging said guide sleeve to move it upwardly.

8. A spear including a mandrel, an ex- 110 pander sleeve thereon, means to support said sleeve, a guide sleeve on said mandrel, a plurality of jaws supported slidably but non-rotatably upon said guide sleeve, said jaws being adapted to fit upon said expander sleeve and means on said mandrel engaging 115 said guide sleeve to move it upwardly and a flange on said mandrel above said ex- pander sleeve for the purpose set forth.

In testimony whereof I hereunto affix my signature this 10th day of July, A. D. 1928.

ERCOLE VENTRESCA.
